UNITED STATES PATENT OFFICE.

GEORGE ALDWORTH, OF LONDON, ENGLAND, ASSIGNOR TO CHARLES NESSLER, OF LONDON, ENGLAND.

PERMANENT-HAIR-WAVING APPLIANCE.

1,186,533.

Specification of Letters Patent. Patented June 13, 1916.

Application filed March 18, 1915. Serial No. 15,261.

To all whom it may concern:

Be it known that I, GEORGE ALDWORTH, subject of the King of Great Britain and Ireland, residing at London, W., England, 5 have invented a new or Improved Permanent-Hair-Waving Appliance, of which the following is a specification.

In the process of permanent hair waving on the human head as at present carried out, 10 it is usual first to wind a tress of hair upon a metal curler and then to cover the hair with a paste or lotion applied either by means of a brush or by means of an absorbent material such as lint or flannel im- 15 pregnated with a paste or lotion. There- after the curler with the tress wound upon it is placed within a paper tube and the whole subjected to the action of a heater. This process is open to the objection that it 20 is a very messy one and further that it re- quires the patient to be subjected to an un- necessarily long treatment as the paste or lotion requires some time for its applica- 25 tion and further treatment.

25 The object of my invention is to avoid having to deal with messy pastes or lotions and the necessity of spending unnecessary time in manipulation. I secure this object by means of what I term my compound tube 30 a device which can be made in quantities for future use and which can be transmitted by rail or post and otherwise handled in a commercial manner. My compound tube has the further advantage that it will last 35 a long time and can be used more than once.

I shall now proceed to describe how my invention is to be or may be carried into effect and for this purpose I shall refer to the accompanying drawings.

40 Figure 1, is a perspective view of the tube blank with the side edges turned up ready to be folded over upon the sheet of material. Fig. 2, is a perspective view of the completed tube blank and a former placed 45 across one end of the blank for rolling the sheet into a tubular body. Fig. 3, is a similar view to that shown in Fig. 2, with the tube blank rolled about half way, and Fig. 4, shows the blank almost completely rolled 50 with its outer end in position to be pasted down. Fig. 5, is a perspective view of the non-absorbent outer cover having the compound tube placed within it. Fig. 6, is a perspective view of a tress of hair wound

on a curler ready to be inserted within the 55 tube.

I take a sheet of absorbent material such for example as stout blotting paper meas- 60uring about five or six inches square and I bend up two opposite sides as shown in Fig. 1 so as to form a shallow trough-shaped tray open at the ends and about half an inch deep. I then take about half an ounce of dry borax powder and distribute this over somewhat more than half of the shallow 65 trough-shaped tray just mentioned so that it will cover the portion 1 to the right of the dotted line 2 while the portion 3 on the left side of the dotted line is left uncovered. I now double down the sides of the paper 70 tray as shown in Fig. 2. I then proceed to roll the paper tray around a "former" into the form of a tube which shall contain the borax powder. The former which I use 75 consists of a cylinder of wood or other con- venient material of about five eighths of an inch in diameter and I place this over the left-hand open end of the tray as shown in Fig. 2. I then roll the parts together so as to wind the paper tray over the former and 80 thus form it into a tube. The diameter of the former is such as to correspond with the diameter of the curler and tress thereon and such that there will be a complete turn 85 of the paper around it before the borax powder is reached. I then continue to roll the paper over the former for another com- plete turn or somewhat more so that I now 90 get a tube consisting roughly of three con- centric turns of respectively absorbent 95 paper, borax powder and absorbent paper again. I now paste down the free edge of the paper, that is to say, the edge 4, so as to prevent the tubes from unrolling. I have 100 now obtained a sandwich-like tube contain- ing a tubular layer of borax powder the ends of the complete tube being formed by the bent down portions of the sheet of paper which were formerly the vertical sides or flanges of the tray, this tube being open at 105 both ends. I now surround this by a tu- bular layer of non-absorbent material such for example as vegetable parchment or tin- foil or the like. This outer tubular covering may be applied as a tube or it may be 110 wound around the tube consisting of absorb- ent material and borax powder, and when the latter plan is adopted the non-absorb-

ent material or a part thereof may be gummed or covered with an adhesive material so as to dispense with the pasting down of the free edge 4 of the inner tube specified. This outer tube of non-absorbent material is longer than the inner tube containing the borax powder by an inch or an inch and a half or thereabout so that it protrudes beyond the inner tube for half an 10 inch or three-quarters of an inch or thereabout at each end.

The compound tube thus formed is now a commercial article and can be handled without the borax powder escaping. For 15 the purpose however of securing against any possibility of escape of the borax powder through rough handling and further to prevent the said powder from "packing" I dip the compound tube momentarily in water so 20 as to moisten it sufficiently to cause the powder to bind.

I find it advantageous to add about two per cent. of hyposulfite of soda to the borax powder although this is not necessary but 15 it appears to have a better effect in softening the hair and adapting it to the process of treatment.

My compound tube is used in the following manner. Having wound a tress of hair 130 over the curler as shown in Fig. 6 the roots of the hair 5 being toward the scalp of the patient, I take the compound tube, still open at both ends, and dip it for about one second of time in cold water and I then pass it 135 over the tress upon the curler. I then ligature the end of the tube which is nearest the scalp tightly by means of a piece of string. The other end of the tube which is remote from the scalp may also be ligatured or simply 140 doubled inward by hand sufficiently to prevent undue escape of moisture during heating. I then apply the heater over the compound tube in the manner well known in this art.

145 I have stated that I immerse the compound tube in water for about one second. In this time the tube usually absorbs about a fifth of an ounce of water which is sufficient for the purpose but an operator very soon 150 learns how long to immerse the tube in water so as to get the best results.

I have found that my compound tube may be used a second time the immersion in water on the second occasion being for a slightly 155 longer period than on the first. My tubes can even be used more than twice but of course with decreasing efficiency.

I have hereinbefore spoken of one complete turn being made over the former before 160 the part of the paper which contains the borax powder is rolled over it and I have spoken of a complete turn being made by the part which contains the borax. I do not of course limit myself to any number of turns 165 or fractions thereof. Nor do I limit myself

to the employment in my compound tubes of borax powder either with or without hyposulfite of soda. I may employ any other reagent that may be found desirable.

I prefer to have the period of immersion 70 for two half seconds. I use that expression because of the popular confusion between seconds and half seconds. Familiarity with clocks beating half seconds has led to such periods being popularly reckoned as full 75 seconds. I however contemplate, in order to avoid mistakes, marking upon each compound tube the time during which it should be immersed in water. This will be useful as the quantity of reagent and the dimensions hereinbefore specified correspond with the average lengths and thicknesses of 80 tresses of ladies' hair. It will of course be understood that such quantity and dimensions will be unsuitable for tresses of unusual length or thickness so that my plan of marking the compound tubes in the manner stated will suit devices of other sizes and having other quantities of reagent. The reagent and the dimensions and the materials 85 cited give good results in practice.

It is to be understood that I do not employ the terms "absorbent" and "non-absorbent" in a strictly absolute sense. They are used in a somewhat comparative sense. 95

Having thus described my invention what I claim as new and desire to secure by Letters Patent is:—

1. As a new article of manufacture a compound hair-treating tube comprising a tubular structure having therein as a constituent part thereof a suitable hair-treating substance normally in condition to withstand transportation and lapse of time but capable under the influence of another element of 100 having its condition altered for application to the hair when inserted within the said tube.

2. As a new article of manufacture a compound tube for hair-waving comprising a tubular body having a chamber or space within its wall and a reagent located therein, the interior surface of said wall having capacity for permitting the contained reagent when changed from its normal condition to 110 act upon the hair when inserted within the tubular body.

3. As a new article of manufacture a compound tube for hair-waving comprising a tubular body formed of two or more plies 120 of material, a reagent placed between plies and forming a constituent part of the article and the innermost ply having capacity for permitting the contained reagent when changed from its normal condition to act 125 upon the hair when inserted within the tubular body.

4. As a new article of manufacture a compound tube for hair-waving comprising a tubular body formed of a plurality of plies 130

of suitable absorbent material, and a reagent interposed between plies of said material so that when the reagent is changed from its normal condition it may act through the 5 material upon the hair when inserted within the tubular body, said reagent forming a constituent part of the article.

5. As a new article of manufacture a compound tube for hair-waving comprising 10 a tubular structure having therein as a constituent part thereof a suitable hair-treating substance normally in condition to withstand transportation and lapse of time but capable under the influence of another element 15 of having its condition altered for application to the hair when inserted within the tube, and a removable outer covering of non-absorbent material for housing said tubular body until used.

20 6. As a new article of manufacture a compound tube for hair-waving comprising a tubular body formed of a plurality of plies of material, a reagent placed between plies and the innermost ply having 25 capacity for permitting the contained reagent when changed from its normal condition to act through said ply upon the hair when inserted within the tubular body, the said reagent being bound in place between

said plies to prevent the reagent from shifting out of place in handling the tube and forming a constituent part of the article. 30

7. As a new article of manufacture a compound tube for hair-waving comprising a tubular body formed of a plurality of plies 35 of material and borax powder placed between plies and forming a constituent part of the article and adapted when changed from its normal condition to act upon the hair when inserted within the tubular body. 40

8. As a new article of manufacture a compound tube for hair-waving comprising a tubular body formed of a plurality of plies of suitable material having inwardly extending flanges on its side edges for confining the reagent within the body, and a reagent interposed between the plies of material and adapted when changed from its normal condition to act upon the hair when inserted within the tubular body. 45

In witness whereof I have signed my name to this specification in the presence of two subscribing witnesses.

GEORGE ALDWORTH.
